RAILWAY TRACK SWITCH CONTROLLING APPARATUS

Henry S. Young, Wilkinsburg, Pa., assignor to
The Union Switch & Signal Company, Swiss-
vale, Pa., a corporation of Pennsylvania

Application March 21, 1935, Serial No. 12,135

5 Claims. (Cl. 246—219)

My invention relates to railway track switch controlling apparatus, and particularly to apparatus of the type involving switch operating mechanism controlled by a manually operable lever or other suitable device subject to given traffic conditions, and is an improvement upon that disclosed in a copending application, Serial No. 11,130, filed March 14, 1935, by Earl M. Allen and Henry S. Young, for Railway traffic controlling apparatus.

One feature of my invention is the provision of novel and improved arrangements for the control of a stick relay for requiring action by the leverman at the time a switch is operated, thereby preventing storage of control for the switch.

I will describe four forms of apparatus embodying my invention, and will then point out the novel features thereof in claims.

In the accompanying drawing, Fig. 1 is a diagrammatic view showing one form of apparatus embodying my invention. Fig. 2 shows a modification of a part of the apparatus of Fig. 1. Fig. 3 is a diagrammatic view of a modified form of the apparatus shown in Fig. 1, also embodying my invention. Fig. 4 is a diagrammatic view of a modified form of the apparatus shown in Fig. 3, and also embodying my invention.

Similar reference characters refer to similar parts in each of the views.

Referring first to Fig. 1, the reference characters 1 and 1^a designate the track rails of a stretch of railway track Y which is divided by insulated joints 2 into sections $B-C$ and $C-D$. Each of these sections is provided with a track circuit, as shown for section $C-D$, comprising a battery, designated by the reference character 3 , connected across the rails adjacent one end of the section, and a relay, designated by the reference character T , connected across the rails adjacent the opposite end of the section.

Located in section $C-D$ is a switch H for connecting track Y with a second track Z . Switch H may be operated by any suitable mechanism such, for example, as a fluid pressure mechanism M comprising a normal control magnet nn and a reverse control magnet rr .

At point C , signals S^a and S^b are shown for controlling eastbound traffic movements, that is, traffic movements from left to right, as shown in the drawing, over switch H in its normal and reverse positions, respectively.

Normal and reverse control magnets nn and rr of switch mechanism M are controlled by a polarized relay designated by the reference character m .

Relay m is so constructed that its neutral contacts are slow in releasing when its control circuit is opened. On account of this characteristic, the front contacts of relay m will not open during the interval between the opening of its pick-up circuits at the front points of contacts 9 and 10 of a stick locking relay R and the closing of stick circuits for relay m through the back points of contacts 9 and 10 of relay R . Relay m is controlled by a manually operable lever k , and by a manually operable latch b associated with lever k , as well as by relay R .

Relay R is controlled by track relay T , by an approach or stick locking relay P , and by latch b . The pick-up circuit for relay R is closed for only a brief period of time, and therefore, in order to insure that relay R closes its front contacts during this brief period, the pick-up circuit for relay R is supplied with current of relatively large magnitude in order to cause relay R to pick up quickly. In order to reduce the holding current from this large magnitude to a magnitude sufficient for retaining the front contacts of relay R closed, a resistor 6 is included in the stick circuit for relay R .

Relay P may be controlled in any suitable manner such, for example, as shown for relay L in a Patent No. 1,956,851, which was granted May 1, 1934, to C. A. Brooks and J. M. Pelikan, for Railway traffic controlling apparatus. The manner in which relay P is controlled prevents a leverman from changing the position of switch H until a measured period of time has elapsed after signal S^a or signal S^b has been caused to indicate stop, if an eastbound train has entered section $B-C$ while one of the signals S is indicating caution or proceed.

Lever k has a normal position n and a reverse position r . Lever k operates a pair of pole-changing contacts 8 and 11 which, when lever k is in its normal position, cause relay m to be energized by current of normal polarity, and when lever k is in its reverse position, cause relay m to be energized by current of reverse polarity.

Manually operable latch b , as here indicated, is connected with lever k at a point 15 . The right-hand end of latch b , as shown in the drawing, is held against a contact arm 14 by a coil spring 16 , one end of which is attached to latch b and the other end of which is attached to a member 17 which is fixed in its relation to latch b . Arm 14 in this position connects with a contact spring 12 . Contact arm 14 is inherently biased toward a second contact spring 13 , and hence when the left-hand end of latch b is manually depressed,

the right-hand end of this latch permits contact arm 14 to leave contact spring 12 and engage contact spring 13.

Fig. 2 shows a modification of lever *k*, from which latch *b* is omitted, and which is so arranged that the contact arm 14 is inherently biased toward contact spring 13, as in Fig. 1, but is forced against contact spring 12 and away from contact spring 13 by lever *k* when lever *k* is at rest in its normal position *n* or its reverse position *r*. In order to be put into a position to operate pole-changing contacts 8 and 11, lever *k* must be removed from engagement with contact arm 14, thus permitting contact arm 14 to leave spring 12 and connect with spring 13. Lever *k*, when thus disengaged from contact arm 14, brings its members 24 and 25 into position to operate pole-changing contacts 11 and 8, respectively, when lever *k* is moved between its normal and reverse positions *n* and *r*.

In Fig. 3, lever *k* is shown equipped with only the pole-changing contacts 8 and 11 which here control a polarized lever repeater relay *L*. Relay *R* is controlled, in part, by a back contact 29 of relay *L* instead of by the latch contact 13-14 of Fig. 1 or lever contact 13-14 of Fig. 2. Relay *m* in Fig. 3 is controlled, in part, by neutral and polar contacts of relay *L* instead of by latch contact 12-14 and lever contacts 8 and 11 of Fig. 1, 30 or lever contacts 12-14, 8 and 11 of Fig. 2.

In Fig. 4, a two-element relay *L* having a line element 34 and a local element 35 is used instead of the single-element relay *L* of Fig. 3. When relay *L* of Fig. 4 is energized by current of one 35 given relative instantaneous polarity, its contacts 36, 38, and 40 are closed as shown in the drawing, and its contacts 37, 39, and 41 are open. When relay *L* is energized by current of the opposite relative instantaneous polarity, its contacts 37, 39, and 41 are closed, and contacts 36, 38, and 40 are open. As here used, relay *R* is of a quick-acting type having one front contact, and hence, in order to obtain more contacts for the control of relay *m*, a second relay *v* is controlled by the one contact of relay *R*.

Having described, in general, the arrangement and operation of the various parts of four forms of apparatus shown in the accompanying drawing, I will now describe in detail the operation 50 of these various forms of apparatus.

As shown in the drawing, all parts of the apparatus are in the normal condition, that is, switch lever *k* and latch *b* are in their normal positions; switch *H* is in its normal position; signals *S* are indicating stop; and relays *m*, *P*, *R*, *T*, *L*, and *v* are energized.

I will first trace the operation of the form of apparatus shown in Fig. 1.

The stick circuit for relay *R*, by which relay 60 *R* is energized, passes from terminal *x* of a suitable source of current not shown in the drawing, through contact 4 of relay *P*, contact 5 of relay *T*, winding of relay *R*, resistor 6, and contact 7 of relay *R* to terminal *o* of the same source 65 of current. With lever *k* and latch *b* in their normal positions and with relay *R* energized, relay *m* is energized by current of normal polarity 70 passing from terminal *x*, through contact 8 of lever *k* in its normal position, front point of contact 9 of relay *R*, winding of relay *m*, front point of contact 10 of relay *R*, contact 11 of lever *k* in its normal position, and contact 12-14 of latch *b* to terminal *o*. With relay *m* energized by current of normal polarity, normal control magnet 75 *nn* of switch mechanism *M* is energized by a cir-

cuit passing from terminal *x*, through contact 21 of relay *m*, contact 22 of relay *m* in its normal position, and magnet *nn* of mechanism *M* to terminal *o*.

I will assume that, with all parts of the apparatus thus in their normal condition, the leverman desires to reverse switch *H*. He will therefore depress latch *b*, thus permitting latch contact 12-14 to open, and closing latch contact 13-14. Contact 13-14, upon becoming closed, 10 completes a pickup circuit which is the same as the stick circuit previously traced for relay *R* as far as the winding of relay *R*, and thence passes through contact 13-14 of latch *b* to terminal *o*.

When lever *k* reaches its reverse position *r*, its 15 pole-changing contacts 8 and 11 will be closed in their reverse positions, latch contact 13-14 will open, and latch contact 12-14 will close, thereby completing a reverse energizing circuit for relay *m*, which is the same as the normal 20 energizing circuit previously traced, except including contacts 8 and 11 of lever *k* in their reverse positions instead of in their normal positions. Relay *m*, upon becoming energized by current of reverse polarity, reverses its polar 25 contacts 18, 20, and 22.

Contact 22, upon being reversed, opens the circuit previously traced for magnet *nn*, and completes a circuit for energizing reverse magnet *rr*, this circuit passing from terminal *x*, through contact 21 of relay *m*, contact 22 of relay *m* in its reverse position, and the winding of magnet *rr* to terminal *o*. Magnet *rr*, upon becoming energized, causes mechanism *M* to move switch *H* to its reverse position.

When the leverman desires to again return switch *H* to its normal position, he will depress latch *b*, thereby again completing the pick-up circuit previously described for relay *R*, and will move lever *k* back to its normal position *n* in 40 which contacts 8 and 11 will again be closed in their normal position, and in which latch contact 13-14 will open and latch contact 12-14 will close and again complete the normal energizing circuit previously traced for relay *m*. 45 With relay *m* again energized by current of normal polarity, normal control magnet *nn* will be energized, causing mechanism *M* to return switch *H* to its normal position.

I will next assume that, with all parts of the apparatus again in their normal condition, the leverman clears signal *S^a* for a train to move over switch *H* in its normal position. By clearing signal *S^a*, the leverman will deenergize relay *P*, thus causing relay *R* to be deenergized. On account of relay *m* being slow in releasing its front contacts, these contacts will remain closed during the interval between the opening of contacts 9 and 10 of relay *R* at their front points and the closing of these contacts at their back points, 60 when a stick circuit will be completed for relay *m*, passing from terminal *x*, through contact 13 of relay *m* in its normal position, back point of contact 9 of relay *R*, winding of relay *m*, back point of contact 10 of relay *R*, contact 19 of relay 65 *m*, and contact 20 of relay *m* in its normal position, to terminal *o*.

When a train passes signal *S^a*, relay *T* will become deenergized, thus opening the circuit for relay *R* at contact 5, in addition to the opening already made in this circuit at contact 4 of relay *P*.

If now while relay *P* or relay *T* is deenergized, the leverman returns the signal control apparatus to the condition for causing signal *S^a* to 75

indicate stop, and if he then operates latch *b* and moves lever *k* to its *r* position, the pick-up circuit for relay *R* will not be closed, on account of contact *4* of relay *P* or contact *5* of relay *T* being open.

I will further assume that the leverman does not at this time return lever *k* to its normal position and that the train proceeds on through sections *B*—*C* and *C*—*D*, permitting relays *P* 10 and *T* to again be energized. With the lever latch *b* in its normal position, the pick-up circuit for relay *R* will not be closed, and hence relay *m* will continue energized by the normal stick circuit previously traced, and therefore switch *H* will not be operated to its reverse position, although lever *k* is in its reverse position *r*.

In order to close the pick-up circuit previously described for relay *R*, the leverman must now 20 depress latch *b*. With relay *R* thus energized, the leverman may again release latch *b*, thereby completing the reverse energizing circuit previously described for relay *m*, which will cause mechanism *M* to move switch *H* to its reverse 25 position.

The operation of the second form of apparatus embodying my invention is similar to that of the first form except that, instead of depressing latch *b* to close the pick-up circuit for relay *R*, the leverman must remove lever *k* from engagement with contact arm *14* shown in Fig. 2. I will assume, for example, that the leverman has cleared signal *S^a*, and that a train has then moved through sections *B*—*C* and *C*—*D*, leaving relay *R* deenergized. I will further assume that the leverman then returns the signal control apparatus to the condition for causing signal *S^a* to indicate stop, and that he then desires to reverse switch *H*. He will therefore move lever *k* from engagement with contact arm *14*, shown in Fig. 2, and will bring lever *k* to the position in which members *24* and *25* of lever *k* will engage contacts *11* and *8*, respectively. With lever contact *13*—*14* of Fig. 2, closed, the pick-up circuit previously described for relay *R* will be completed. With members *24* and *25* of lever *k* engaging contacts *11* and *8*, respectively, the leverman will move lever *k* to its reverse position, thereby reversing contacts *8* and *11*, 50 and thus causing relay *m* to be energized by current of reverse polarity, which will in turn cause switch *H* to be moved to the reverse position as described for the operation of the form of apparatus shown in Fig. 1.

As shown in Fig. 3, relay *L* is energized in the normal direction by a circuit passing from terminal *x*, through contact *8* of lever *k* in its normal position, winding of relay *L*, and contact *11* of lever *k* in its normal position to terminal *o*. Relay *R* is energized by its stick circuit previously traced in connection with Fig. 1. With relay *L* energized by current of normal polarity, and with relay *R* energized, relay *m* is energized in the normal direction by a circuit passing from terminal *x*, through contact *30* of relay *L*, contact *31* of relay *L* in its normal position, front point of contact *9* of relay *R*, winding of relay *m*, front point of contact *10* of relay *R*, contact *32* of relay *L* in its normal position, and contact *33* of relay *L* to terminal *o*.

For an example of the operation of the apparatus shown in Fig. 3, I will assume that relay *R* is deenergized as previously described in connection with the operation of the second form 75 of apparatus. I will also assume that the lever-

man, in order to reverse switch *H*, moves lever *k*, of the form of apparatus shown in Fig. 3, to the reverse position. If this movement of the lever is slow enough, the deenergization of relay *L* will cause back contact *29* of relay *L* to close before lever *k* reaches its *r* position. If, however, contact *29* does not close before lever *k* reaches its *r* position, the reversal of polarity of the current supplied to relay *L* when lever *k* reaches its *r* position will cause contact *29* to close momentarily.

With contact *29* of relay *L* closed in either manner, a pick-up circuit will be completed for relay *R*, which is the same as the pick-up circuit described for Fig. 1, as far as the winding 15 of relay *R*, and thence passes through contact *29* of relay *L* to terminal *o*. Relay *R* will then be retained in the energized condition by its stick circuit previously traced for Fig. 1.

Relay *L*, upon becoming energized by current 20 of reverse polarity on account of lever *k* being moved to its *r* position, will shift its polar contacts *31* and *32* to their reverse positions, and will then close its front contacts *30* and *33*, thereby completing a reverse energizing circuit for 25 relay *m* which is the same as the normal energizing circuit previously traced for relay *m*, except that it includes contacts *31* and *32* of relay *L* in their reverse positions instead of in their normal position. With relay *m* thus energized by 30 current of reverse polarity, mechanism *M* will move switch *H* to its reverse position.

As shown in Fig. 4, line element *34* of relay *L* is energized by current of normal instantaneous relative polarity through a circuit passing from 35 terminal *BX* of a suitable source of alternating current not shown in the drawing, through contact *8* of lever *k* in its normal position, line element *34* of relay *L*, and contact *11* of lever *k* in its normal position to terminal *CX* of the same 40 source of alternating current. Local element *35* of relay *L* is constantly energized from the same source of alternating current. Relay *R* is energized by its stick circuit which is the same as the stick circuit previously traced in connection with 45 Fig. 1. With relay *R* energized, relay *v* is also energized by a circuit passing from terminal *x*, through contact *4* of relay *P*, contact *5* of relay *T*, winding of relay *v*, and contact *7* of relay *R* to terminal *o*. With relays *L* and *v* energized as just described, relay *m* is energized in the normal direction by a circuit passing from terminal *x*, through contact *38* of relay *L*, front point of contact *9* of relay *v*, winding of relay *m*, front point of contact *16* of relay *v*, and contact *40* 55 of relay *L* to terminal *o*.

For an example of the operation of the apparatus shown in Fig. 4, I will assume that relays *R* and *v* are deenergized on account of relays *P* and *T* having been deenergized, but that relays *P* and *T* are now again energized. I will further assume that the leverman now moves lever *k* to its *r* position to reverse switch *H*. Contact *37* of relay *L* will be closed for a very brief period before contact *36* of relay *L* opens due to the reversal of lever *k*, but relay *R*, being very quick acting, will close its contact *7* during this brief period in which relay *R* will be energized by a pick-up circuit which is the same as the pick-up circuit previously described for relay *R* of Fig. 1, as far as 70 the winding of relay *R*, and thence passes through contacts *36* and *37* of relay *L* to terminal *o*. Relay *R*, upon closing its contact *7*, completes the circuit previously traced for relay *v* which then becomes energized. With relay *v* now energized, 75

and with relay L energized by current of reverse instantaneous relative polarity, a reverse energizing circuit will be completed for relay m, passing from terminal x, through contact 39 of relay 5 L, front point of contact 10 of relay v, winding of relay m, front point of contact 9 of relay v, and contact 41 of relay L to terminal o. With relay m thus energized by current of reverse polarity, mechanism M will move switch H to its 10 reverse position.

From the foregoing descriptions and the accompanying drawing, it follows that apparatus embodying my invention includes a stick relay which is so controlled that, in order for a switch 15 to be operated, the leverman must take some action, either with the switch lever or with an auxiliary contact device, at a time when traffic conditions are suitable for operation of the switch. Any action taken by the leverman while 20 traffic conditions are unsuitable for operation of the switch will be ineffective to cause operation of the switch when the traffic conditions have again become suitable for operation of the switch.

25 Although I have herein shown and described only four forms of railway track switch controlling apparatus embodying my invention, it is understood that various changes and modifications may be made therein within the scope of 30 the appended claims without departing from the spirit and scope of my invention.

Having thus described my invention, what I claim is:

1. In combination, a stretch of railway track 35 including a switch, a manually operable switch lever having a normal and a reverse position and having a normal and a reverse contact closed only when said lever is in said normal and reverse positions respectively, a third contact associated with said lever and which is normally open 40 but which is arranged to be closed if said lever is moved between its normal and reverse positions, a stick relay, a pick-up circuit for said stick relay controlled by traffic conditions in said 45 stretch and including said third contact for supplying said stick relay with sufficient current to cause said stick relay to close its front contacts quickly, a resistor, a stick circuit for said stick relay controlled by said traffic conditions independently of said third contact and including said 50 resistor for reducing the magnitude of the current in said stick circuit to a suitable value, and means controlled by said normal and reverse contacts for operating said switch to its normal and 55 reverse positions if and only if a front contact of said stick relay is closed.

2. In combination, a stretch of railway track 60 including a switch, a manually operable switch lever having a normal and a reverse position, a stick relay, a pick-up circuit for said stick relay controlled by traffic conditions in said stretch and which is normally open when said lever is in either the normal or the reverse position but which becomes closed if said lever is moved between its 65 normal and reverse positions while said traffic conditions are suitable for said switch to be operated from one of its extreme positions to the other, a resistor, a stick circuit for said stick relay controlled by said traffic conditions inde-

pendently of said lever and including said resistor for reducing the magnitude of the current in said stick circuit to a value suitable for retaining a front contact of said relay closed, and means controlled by said lever in its normal and reverse positions for operating said switch to its normal and reverse positions if and only if a front contact of said stick relay is closed. 5

3. In combination, a stretch of railway track 10 including a switch, a manually operable switch lever having a normal and a reverse position, a manually operable contact which is normally open but which is manually closed when said lever is conditioned to be operated between said normal and reverse positions, a stick relay, a pick-up 15 circuit for said stick relay controlled by said manually operable contact and by traffic conditions in said stretch, a stick circuit for said stick relay controlled by traffic conditions in said stretch independently of said manually operable contact, and means controlled by said lever in its normal and reverse positions for operating said 20 switch to its normal and reverse positions if and only if a front contact of said stick relay is closed and said manually operable contact is in its normal position. 25

4. In combination, a stretch of railway track including a switch, a manually operable switch lever having a normal and a reverse position, a manually operable contact which is normally closed in a first position but which is manually opened at said first position and closed in a second position when said lever is conditioned to be operated between said normal and reverse positions, a stick relay, a pick-up circuit for said stick 35 relay closed by said contact in its second position if traffic conditions in said stretch are suitable for said switch to be operated, a stick circuit for said stick relay for retaining said stick relay energized independently of said manually operable 40 contact if traffic conditions in said stretch are suitable for said switch to be operated, and means controlled by said lever in its normal and reverse positions for operating said switch from one of its extreme positions to the other if and only if a 45 front contact of said stick relay is closed and if said manually operable contact is closed in its first position.

5. In combination, a stretch of railway track 50 including a switch, a manually operable pole-changer having a normal and a reverse position, a polarized relay having a back neutral contact as well as normal and reverse polar contacts, means controlled by said pole-changer in its normal and reverse positions for energizing said polarized 55 relay by current of normal and reverse polarity respectively, a stick relay, a pick-up circuit for said stick relay controlled by traffic conditions in said stretch and by the back neutral contact of said polarized relay, a stick circuit for said stick 60 relay controlled by traffic conditions in said stretch independently of said back contact, and means controlled by a front contact of said stick relay and by the normal and reverse polar contacts of said polarized relay for operating said 65 switch to its normal or its reverse position according as the polarized relay is energized by current of normal or of reverse polarity.

HENRY S. YOUNG.
